Patented Oct. 11, 1960

188,990

FLOWER POT SHELF UNIT

Edward L. Lowe, 638 Park Drive, Statesville, N.C.

Filed May 13, 1959, Ser. No. 55,898

Term of patent 3½ years

(Cl. D35—3)

I claim:

The ornamental design for a flower pot shelf unit, substantially as shown.
